US0D1043096S

(12) **United States Design Patent** (10) **Patent No.:** **US D1,043,096 S**
(45) **Date of Patent:** **** Sep. 24, 2024**

(54) **UMBRELLA BASE**

(71) Applicant: **Shenzhen Youchong Technology Co., Ltd.**, Guangdong (CN)

(72) Inventor: **Xiaoqian Li**, Guangdong (CN)

(***) Term: **15 Years**

(21) Appl. No.: **29/902,777**

(22) Filed: **Sep. 15, 2023**

(51) **LOC (14) Cl.** **03-03**

(52) **U.S. Cl.**

USPC **D3/10**

(58) **Field of Classification Search**

Rhino Square Umbrella Base Weight, 18" Fits Any Offset, Cantilever & Any Outdoor Patio Umbrella Stand, amazon.com, https://www.amazon.com/Rhino-Umbrella-Weights-Opening-Cantilever/dp/B07N2ZFWJD?ref_=ast_sto_dp&th=1 (Year: 2020).*

Primary Examiner — Steven J Czyz

(57) **CLAIM**

The ornamental design for a umbrella base, as shown and described.

DESCRIPTION

FIG. 1 is a perspective view of the umbrella base showing my new design;

FIG. 2 is a another perspective view of the umbrella base showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 a partial enlarged view of portion 9 in FIG. 1; and,

FIG. 10 a partial enlarged view of portion 10 in FIG. 2.

The broken lines in the figures illustrate portions that form no part of the claimed design.

1 Claim, 10 Drawing Sheets
